ABSTRACT

A coil component having a structure that can easily realize a desired positional relationship between a cover member and a bobbin portion is provided. The coil component includes a bobbin portion, a magnetic core inserted through the bobbin portion, and a coil wound around the bobbin portion, and a cover member covering the bobbin portion by being externally fitted to the bobbin portion. In the coil component, the cover member and the bobbin portion abut each other, and at least one of the cover member and the bobbin portion elastically biases the other in a first direction parallel to a mounting surface.

COIL COMPONENT

CROSS-REFERENCE TO RELATED APPLICATIONS

This application claims the benefit of Japanese Patent Application No. 2020-029261 filed on Feb. 25, 2020 in the Japanese Patent Office, the disclosure of which is incorporated by reference herein in its entirety.

BACKGROUND

Field of the Invention

The present invention relates to a coil component.

Related Art

A coil component is disclosed in Japanese Laid-open patent publication NO. 2014-236128, for example.

The coil component in Japanese Laid-open patent publication NO. 2014-236128 includes a bobbin portion (described as a bobbin in the document), a coil wound around the bobbin portion, a magnetic core inserted through the bobbin portion, and a cover member (described as a case in the document) covering the bobbin portion.

According to the study by the inventors of the present application, the structure of the coil component in Japanese Laid-open patent publication NO. 2014-236128 has room for improvement from the viewpoint of realizing a desired positional relationship between the cover member and the bobbin portion.

The present invention has been made in view of the above issue and provides a coil component having a structure that can easily realize a desired positional relationship between a cover member and a bobbin portion.

SUMMARY

According to the present invention, there is provided a coil component comprising:

a bobbin portion;
a magnetic core inserted through the bobbin portion;
a coil wound around the bobbin portion; and
a cover member covering the bobbin portion by being externally fitted to the bobbin portion, wherein the cover member and the bobbin portion abut each other, and at least one of the cover member and the bobbin portion elastically biases the other in a first direction parallel to a mounting surface.

According to the present invention, it is possible to easily realize a desired positional relationship between the cover member and the bobbin portion.

BRIEF DESCRIPTION OF THE DRAWINGS

The above and other objects, advantages and features of the present invention will be more apparent from the following description of certain preferred embodiments taken in conjunction with the accompanying drawings, in which:

FIG. 1 is a perspective view of a coil component according to an embodiment;

FIG. 2 is an exploded perspective view of the coil component according to the embodiment;

FIG. 3 is a front view of the coil component according to the embodiment;

2

FIG. 4 is a plan view of the coil component according to the embodiment;

FIG. 5 is a bottom view of the coil component according to the embodiment;

FIG. 6 is a cross-sectional view taken along line A-A in FIG. 4;

FIG. 7 illustrates a cover member according to the embodiment in a cross-sectional view taken along line A-A of FIG. 4;

FIG. 8 is a perspective view of the cover member and a main body member according to the embodiment; and

FIGS. 9A, 9B, and 9C illustrate the main body member according to the embodiment, where FIG. 9A is a perspective view, FIG. 9B is a front view, and FIG. 9C is a plan view.

DETAILED DESCRIPTION

The invention will be now described herein with reference to illustrative embodiments. Those skilled in the art will recognize that many alternative embodiments can be accomplished using the teachings of the present invention and that the invention is not limited to the embodiments illustrated for explanatory purposes.

25 The following describes the embodiments of the present invention with reference to FIGS. 1 to 9C. Note that a first fixing tape 90 and a second fixing tape 95 are not shown in FIGS. 1 and 3. In FIGS. 1, 3, and 4, a main body member 20 is indicated by dotted lines. In FIG. 4, a coil 70 is also indicated by dotted lines. FIG. 8 illustrates a state in which a cover member 80 and a main body member 20 are assembled to each other.

30 Note that the same reference characters are given to the similar components in all the drawings, and the descriptions thereof will not be repeated.

35 As shown in any of FIGS. 1 to 9C, a coil component 100 according to this embodiment includes a bobbin portion 30, a magnetic core 10 inserted through the bobbin portion 30, a coil 70 wound around the bobbin portion 30, and a cover member 80 covering the bobbin portion 30 by being externally fitted to the bobbin portion 30.

40 In the coil component 100, the cover member 80 and the bobbin portion 30 abut each other, and at least one of the cover member 80 and the bobbin portion 30 elastically biases the other in a first direction parallel to a mounting surface. The phrase “the other” here refers to the one of the cover member 80 and the bobbin portion 30 that is elastically biased (a counterpart).

45 Here, to elastically bias means that at least one of the cover member 80 and the bobbin portion 30 elastically deforms and the one elastically biases the counterpart with its elastic restoring force.

50 In addition, to bias in the first direction means that, when the biasing force is vector-resolved into three directions: the first direction; a direction parallel to the mounting surface and orthogonal to the first direction; and a direction orthogonal to the mounting surface, the component of the first direction is the largest of these three directions.

55 According to this embodiment, at least one of the cover member 80 and the bobbin portion 30 elastically biases the other in the first direction. Therefore, even if there is a manufacturing variation in the dimension of one or both of the cover member 80 and the bobbin portion 30 in the first direction, the cover member 80 and the bobbin portion 30 can be positioned to each other in the first direction, so that the misalignment between the cover member 80 and the bobbin portion 30 in the first direction can be suppressed.

Moreover, at least one of the cover member **80** or the bobbin portion **30** can elastically deform in conformity with the manufacturing variation to absorb the manufacturing variation. Thus, it is possible to easily realize a desired positional relationship between the cover member **80** and the bobbin portion **30**.

In the following description, the up-down direction will be referred to as a Z direction. The lower (down) side is the side on which terminal portions **60** (FIG. 1, etc.), which will be described later, are arranged, that is, the side toward a mounting surface onto which the coil component **100** is mounted. However, the positional relationships (in particular, the positional relationships in the up-down direction) between parts during manufacture and use of the coil component **100** are not limited to the positional relationships described herein.

The axial direction of the coil **70** extends in a direction orthogonal to the Z direction. The axial direction of the coil **70** is referred to as an X direction, one side in the X direction is referred to as a right (rightward) side, and the other is referred to as a left (leftward) side.

A direction orthogonal to both of the X direction and the Z direction is referred to as a Y direction, one side in the Y direction is referred to as a front (frontward) side, and the other is referred to as a rear (rearward) side.

These directions are indicated in each figure.

Further, in the X direction, the side on which the center position of the coil **70** in the axial direction of the coil **70** is located is referred to as an inward (inner) side, and the side opposite to the inward side is referred to as an outward (outer) side. Similarly, in the Y direction, the side on which the center position of the coil **70** in the front-rear direction is located is referred to as an inward (inner) side, and the side opposite to the inward side is referred to as an outward (outer) side.

An orientation (direction) orthogonal to the Z direction is referred to as horizontal (horizontal direction), and an orientation (direction) along the Z direction is referred to as vertical (vertical direction).

As shown in FIG. 2, in the case of this embodiment, the magnetic core **10** includes a pair of left and right core members, namely a first core member **11a** arranged on the right side and a second core member **11b** arranged on the left side, for example.

Each of the first core member **11a** and the second core member **11b** is what is called an E core and is formed to have an E-shaped planar shape (see FIG. 4), for example.

More specifically, the first core member **11a** includes a base portion **12** extending in the front-rear direction, a pair of outer leg portions **13** protruding leftward from both end portions of the base portion **12**, and a core portion **15** protruding leftward from an intermediate portion of the base portion **12**. The direction in which the outer leg portions **13** and the core portion **15** protrude from the base portion **12** is the same as the axial direction of the coil **70**.

The base portion **12** is formed in a prismatic shape that is long in the front-rear direction and has a rectangular cross section orthogonal to the axial direction, for example. Two of the four surfaces of the base portion **12** arranged around its axis are an upper surface and a lower surface that are horizontal, one of the remaining two surfaces (hereinafter, an inner side surface **12c**) faces toward the bobbin portion **30**, and the other (hereinafter, an outer side surface **12d**) faces opposite the bobbin portion **30**. In the case of this embodiment, the inner side surface **12c** of the base portion **12** of the first core member **11a** forms the inner side surface

of the first core member **11a**, and the outer side surface **12d** of the base portion **12** forms the outer side surface of the first core member **11a**.

Each outer leg portion **13** and the core portion **15** are formed in a prismatic shape that is long in the left-right direction and have a rectangular cross section orthogonal to the axial direction, for example. Two of the four surfaces of the outer leg portion **13** and the core portion **15** arranged around these axes are an upper surface and a lower surface that are horizontal, one of the remaining two surfaces faces forward, and the other faces rearward.

The base portion **12**, each outer leg portion **13**, and the core portion **15** are set to have the same up-down dimension, for example. In the first core member **11a**, the upper surface of the base portion **12**, the upper surfaces of the outer leg portions **13**, and the upper surface of the core portion **15** are arranged flush with each other. That is, the entire upper surface of the first core member **11a** is formed flat and arranged horizontally. Similarly, in the first core member **11a**, the lower surface of the base portion **12**, the lower surfaces of the outer leg portions **13** and the lower surface of the core portion **15** are arranged flush with each other. That is, the entire lower surface of the first core member **11a** is formed flat and arranged horizontally.

The second core member **11b** is formed in the same shape as the first core member **11a**, for example. That is, the second core member **11b** includes a base portion **12**, a pair of outer leg portions **13**, and a core portion **15**. The base portion **12** has an upper surface, a lower surface, an inner side surface **12c**, and an outer side surface **12d**.

The second core member **11b** is arranged to have a left-right symmetry with the first core member **11a**.

The end surface of each outer leg portion **13** of each of the first core member **11a** and the second core member **11b** in the protruding direction is formed flat and is a vertical surface orthogonal to the axial direction of the coil **70**.

Similarly, the end surface of the core portion **15** of each of the first core member **11a** and the second core member **11b** in the protruding direction is formed flat and is a vertical surface orthogonal to the axial direction of the coil **70**.

As shown in FIG. 4, the inner side surface **12c** and the outer side surface **12d** of the base portion **12** are also formed flat and are vertical surfaces orthogonal to the axial direction of the coil **70**. The inner side surface of the first core member **11a** and the inner side surface of the second core member **11b** face each other, and the outer side surface of the first core member **11a** and the outer side surface of the second core member **11b** face opposite to each other.

As shown in FIG. 2, the coil component **100** further includes a main body member **20** including the bobbin portion **30** and terminal holding portions **50**, and a plurality of terminal portions **60** held by the terminal holding portions **50**. A winding wire **71** forming the coil **70** is wound around the bobbin portion **30**.

The bobbin portion **30** includes a tubular portion **31** and a pair of collar portions **40** provided at both end portions of the tubular portion **31** in the axial direction, for example.

The tubular portion **31** is formed in a rectangular tubular shape having a through hole **36** penetrating therethrough in the axial direction. The axial direction of the tubular portion **31** (the axial direction of the through hole **36**) is the left-right direction, which coincides with the axial direction of the coil **70**.

As shown in FIGS. 9B and 9C, the tubular portion **31** includes an upper wall portion **32** and a lower wall portion

33 that are arranged horizontally, and a front wall portion 34 and a rear wall portion 35 that are arranged vertically, for example.

For example, the internal space of the through hole 36 has a prismatic shape. The bottom surface (inner peripheral bottom surface) and the top surface of the inner peripheral surface of the through hole 36 are horizontal surfaces, and the front and rear surfaces of the inner peripheral surface of the through hole 36 are vertical surfaces.

As shown in FIGS. 9A, 9B, and 9C, the bobbin portion 30 includes a pair of collar portions 40, namely a first collar portion 41 arranged on the right side and a second collar portion 42 arranged on the left side, for example.

Each of the first collar portion 41 and the second collar portion 42 juts out from both end portions of the tubular portion 31 toward the external surrounding space of the tubular portion 31, for example.

More specifically, the first collar portion 41 is formed in a flat plate shape orthogonal to the axial direction of the tubular portion 31, for example. The second collar portion 42 is formed in a flat rectangular parallelepiped shape of which the left-right dimension is smaller than each of the up-down dimension and the front-rear dimension, and each of the right-side and left-side surfaces is orthogonal to the first direction, for example.

The left-right dimension (thickness dimension) of the first collar portion 41 is smaller than the left-right dimension (thickness dimension) of the second collar portion 42. The front-rear dimension of the first collar portion 41 is equal to the front-rear dimension of the second collar portion 42, and the up-down dimension of the first collar portion 41 is equal to the up-down dimension of the second collar portion 42.

Further, the front end surface of the first collar portion 41 and the front surface of the second collar portion 42 are arranged flush with each other, and the rear end surface of the first collar portion 41 and the rear surface of the second collar portion 42 are arranged flush with each other.

A concave portion 42a is formed at a central portion of the upper surface of the second collar portion 42 in the front-rear direction, for example. The concave portion 42a is recessed downward and opens leftward.

As shown in FIGS. 9A, 9B, and 9C, the main body member 20 includes, as the terminal holding portions 50, a first terminal holding portion 52 arranged on the right side and a second terminal holding portion 55 arranged on the left side.

The first terminal holding portion 52 is formed in a flat prismatic shape that is long in the front-rear direction and of which the left-right dimension is smaller than the up-down dimension, for example.

The second terminal holding portion 55 is formed in a flat plate shape that is long in the front-rear direction and of which the up-down dimension is smaller than the left-right dimension, for example.

On the lower surface of the second terminal holding portion 55, a jutting portion 59 (see FIGS. 2 and 3) hung from the right edge portion of the second terminal holding portion 55 is formed, for example. The jutting portion 59 is formed in a flat plate shape whose plate surface faces in the left-right direction. The right side surface of the jutting portion 59 is arranged flush with the right side surface of the second terminal holding portion 55.

The first terminal holding portion 52 juts out from the lower edge of the first collar portion 41 in the rightward and front-rear directions. The second terminal holding portion 55 juts out from the lower edge of the second collar portion 42 in the leftward and front-rear directions.

In the case of this embodiment, the left-right dimension of the first terminal holding portion 52 is smaller than the left-right dimension of the second terminal holding portion 55. The up-down dimension of the first terminal holding portion 52 is larger than the up-down dimension of the second terminal holding portion 55 (the portion excluding the jutting portion 59). The front-rear dimension of the first terminal holding portion 52 is equal to the front-rear dimension of the second terminal holding portion 55. The height position of the lower end surface of the jutting portion 59 is equal to the height position of the lower end surface of the first terminal holding portion 52.

However, the dimensional relationship between the first terminal holding portion 52 and the second terminal holding portion 55 is not particularly limited, and the first terminal holding portion 52 and the second terminal holding portion 55 may have the same size.

The upper surfaces of the first terminal holding portion 52 and the second terminal holding portion 55 are formed flat and arranged horizontally.

The first terminal holding portion 52 holds a first terminal portion 61, a second terminal portion 62, and a third terminal portion 63, which will be described later, for example. The second terminal holding portion 55 holds a fourth terminal portion 64, which will be described later, for example.

As shown in FIGS. 4 and 5, in the case of this embodiment, the coil component 100 includes, as the terminal portions 60, the first terminal portion 61, the second terminal portion 62, the third terminal portion 63, and the fourth terminal portion 64, for example.

At the first terminal holding portion 52, the first terminal portion 61 to the third terminal portion 63 are arranged side by side in the front-rear direction in the order of the first terminal portion 61, the second terminal portion 62, and the third terminal portion 63 from the front side. The fourth terminal portion 64 is arranged at the second terminal holding portion 55.

The first terminal portion 61 is formed by bending a long plate-shaped metal material, for example.

As shown in FIGS. 2 and 3, the first terminal portion 61 has two end portions exposed to the outside from the first terminal holding portion 52 and an intermediate portion (not shown in the drawings) embedded in the first terminal holding portion 52. The one of the two exposed end portions that is arranged on the upper side is an entwining terminal 66 around which an end portion of the corresponding winding wire 71 is entwined, and the end portion arranged on the lower side is an external terminal 65 that is externally connected when the coil component 100 is mounted.

More specifically, the first terminal portion 61 is folded back inside the first terminal holding portion 52, and in front view, the first terminal portion 61 has a horizontally laid U-shape.

The entwining terminal 66 of the first terminal portion 61 extends horizontally and rightward from the right side surface of the first terminal holding portion 52. The external terminal 65 of the first terminal portion 61 protrudes downward from the bottom surface of the first terminal holding portion 52 and extends rightward.

For example, the third terminal portion 63 is formed in a same shape with the first terminal portion 61. Therefore, the third terminal portion 63 has an external terminal 65 and an entwining terminal 66 exposed to the outside from the first terminal holding portion 52 and an intermediate portion (not shown in the drawings) embedded in the first terminal holding portion 52.

The second terminal portion 62 is formed by bending a metal material having a plate shape that is long and is forked in the downward direction, for example.

As shown in FIGS. 2 and 6, the second terminal portion 62 has a pair of front and rear leg portions 62b exposed to the outside from the bottom surface of the first terminal holding portion 52, an extending portion 62c exposed to the outside from the right side surface of the first terminal holding portion 52, and a connecting portion (not shown in the drawings) embedded in the first terminal holding portion 52 and connecting the pair of leg portions 62b and the extending portion 62c.

The pair of leg portions 62b is external terminals 65 that are externally connected when the coil component 100 is mounted, and the extending portion 62c is an entwining terminal 66 around which an end portion of the corresponding winding wire 71 is entwined.

The second terminal portion 62 is folded back inside the first terminal holding portion 52, and in front view and plan view, the second terminal portion 62 has an up-down inverted U-shape that opens downward.

The entwining terminal 66 of the second terminal portion 62 extends horizontally and rightward from the right side surface of the first terminal holding portion 52. Each external terminal 65 of the second terminal portion 62 protrudes downward from the bottom surface of the first terminal holding portion 52 and extends rightward.

The left-right length dimensions of the external terminals 65 of the first terminal portion 61 to the third terminal portion 63 are set to be equal to each other, for example.

Also, the thickness dimensions of the plate-shaped metal materials forming the first terminal portion 61 to the third terminal portion 63 are set to be equal to each other.

The fourth terminal portion 64 is formed by bending a metal material having a plate shape that is long and is forked in the downward direction, for example.

As shown in FIGS. 3 and 6, the fourth terminal portion 64 has a pair of front and rear leg portions 64b exposed to the outside from the bottom surface of the second terminal holding portion 55 and a connecting portion 64a embedded in the second terminal holding portion 55 and the second collar portion 42 and connecting the pair of leg portions 64b.

The pair of leg portions 64b is external terminals 65 that are externally connected when the coil component 100 is mounted.

The fourth terminal portion 64 is folded back inside the second terminal holding portion 55 and the second collar portion 42, and in side view and plan view, the fourth terminal portion 64 has an up-down inverted U-shape that opens downward.

As shown in FIGS. 9A and 9C, the central portion of the upper surface of the connecting portion 64a in the front-rear direction is exposed to the outside from the bottom surface of the concave portion 42a of the second collar portion 42, and in the exposed portion, the connecting portion 64a has a protruding portion 64c protruding upward, for example.

Each external terminal 65 protrudes downward from the bottom surface of the second terminal holding portion 55 and extends leftward, for example.

The left-right length dimensions of the external terminals 65 of the fourth terminal portion 64 are set to be equal to each other, for example.

The thickness dimension of the plate-shaped metal material forming the fourth terminal portion 64 is larger than the thickness dimension of the plate-shaped metal materials forming the first terminal portion 61 to the third terminal portion 63, for example.

The coil component 100 includes a first coil and a second coil as the coil 70, for example.

The first coil and the second coil are formed by respective winding wires 71. Each winding wire 71 of the coil 70 is wound around the tubular portion 31 of the bobbin portion 30. A winding portion 72 (see FIG. 2) is formed by the winding wire 71 wound around the tubular portion 31. Both end portions of each winding wire 71 are each electrically connected to the corresponding terminal portion 60.

10 Note that the end portions of the winding wires 71 are entwined around the entwining terminals 66 and the portions extending from the winding portion 72 toward the terminal portions 60 are not shown in the drawings.

As shown in FIGS. 2, 4, 6 and 8, the cover member 80 has a side peripheral wall portion 82 (a first side peripheral wall portion 82) having a rectangular prismatic tubular shape and including a first wall portion 82a, a second wall portion 82b, a third wall portion 82c, and a fourth wall portion 82d, for example.

15 The cover member 80 also has a top surface portion 81 (see FIG. 2, etc.) closing the upper end of the side peripheral wall portion 82. Further, as shown in FIGS. 2, 6 and 7, the cover member 80 opens downward, for example.

The first wall portion 82a to the fourth wall portion 82d are each formed in a flat plate shape and arranged vertically.

20 As shown in FIGS. 4 and 6, the first wall portion 82a and the second wall portion 82b face each other, and the third wall portion 82c and the fourth wall portion 82d face each other, for example. More specifically, the plate surfaces (wall surfaces) of the first wall portion 82a and the second wall portion 82b face in the left-right direction, for example. The plate surfaces (wall surfaces) of the third wall portion 82c and the fourth wall portion 82d face in the front-rear direction, for example.

25 The top surface portion 81 is formed in a flat plate shape and arranged horizontally, for example. Since the cover member 80 has the top surface portion 81, the top surface portion 81 can be adsorbed by a mounter in mounting the coil component 100 on a board, and the work of mounting 30 the coil component 100 on the board can be easily performed.

35 The top surface portion 81 may not be formed flat. The cover member 80 may also have a shape that does not have the top surface portion 81 (for example, a shape that 40 opens upward and downward).

The cover member 80 has a protruding portion 81a (see FIGS. 1 and 3) protruding leftward from a rear portion of the left side surface of the top surface portion 81, for example. By virtue of the protruding portion 81a, the orientation of 45 the cover member 80 can be easily recognized.

50 As described above, the cover member 80 is arranged to cover the bobbin portion 30, for example. More specifically, as shown in FIG. 4, the first wall portion 82a covers the right side of the bobbin portion 30, the second wall portion 82b covers the left side of the bobbin portion 30, the third wall portion 82c covers the front side of the bobbin portion 30, and the fourth wall portion 82d covers the rear side of the 55 bobbin portion 30, for example. As shown in FIG. 3, the top surface portion 81 covers the upper side of the bobbin portion 30.

50 Since the cover member 80 covers the bobbin portion 30 in this manner, it is possible to obtain a sufficient voltage 60 withstanding property of the coil component 100.

As shown in FIGS. 2 and 3, a through opening 88a 65 penetrating the first wall portion 82a in the left-right direction is formed in the first wall portion 82a, for example. Similarly, a through opening 88b penetrating the second wall

portion **82b** in the left-right direction is formed in the second wall portion **82b**, for example. The through opening **88a** and the through opening **88b** are arranged to face each other.

The through opening **88b** of the second wall portion **82b** is formed in a rectangular shape that is substantially equal to the shape of the through hole **36** of the bobbin portion **30** as viewed in the axial direction, for example. On the other hand, the through opening **88a** of the first wall portion **82a** is formed in a substantially rectangular shape that is long in the front-rear direction (see FIG. 8), for example. The upper edge and the lower edge of the through opening **88a** are arranged horizontally. Similarly, the upper edge and the lower edge of the through opening **88b** are arranged horizontally.

In the case of this embodiment, the direction in which the first wall portion **82a** and the second wall portion **82b** face each other is the first direction, as an example. As described above, in the case of this embodiment, the direction in which the first wall portion **82a** and the second wall portion **82b** face each other is the left-right direction. Therefore, the first direction coincides with the axial direction of the coil **70** and the extending direction of the tip portion of each external terminal **65** (see FIG. 4).

Here, a direction parallel to the mounting surface and orthogonal to the first direction is referred to as a second direction. In the case of this embodiment, the direction in which the third wall portion **82c** and the fourth wall portion **82d** face each other is the second direction orthogonal to the first direction, as an example. As described above, in the case of this embodiment, the direction in which the third wall portion **82c** and the fourth wall portion **82d** face each other is the front-rear direction. Therefore, the second direction is a direction orthogonal to the axial direction of the coil **70** and the extending direction of the tip portion of each external terminal **65** (see FIG. 4).

However, in the present invention, the first direction and the second direction are not limited to the above-described example, and can be appropriately set according to the structure of each member forming the coil component **100**, the positional relationship between the members to be realized, and the like.

As shown in FIG. 6, the cover member **80** further has a flange portion **86** jutting out from the lower end of the side peripheral wall portion **82** to the surrounding space (in the horizontal direction) and a second side peripheral wall portion **85** hung from the peripheral edge of the flange portion **86** and surrounding the terminal holding portions **50**.

The flange portion **86** is formed in a flat plate shape and arranged horizontally, for example. An upper surface **86a** and a lower surface of the flange portion **86** are horizontal surfaces formed substantially flat. However, a protruding portion protruding downward may be formed on the lower surface of the flange portion **86**, for example.

As shown in FIG. 4, the second side peripheral wall portion **85** is formed in a rectangular shape in plan view, and the internal space of the second side peripheral wall portion **85** is formed in a rectangular parallelepiped shape, for example. The lower end of the second side peripheral wall portion **85** opens downward. In the case of this embodiment, the lower end-side opening of the second side peripheral wall portion **85** forms the opening of the cover member **80**.

The second side peripheral wall portion **85** has a first wall portion **85a** surrounding the right side of the terminal holding portion **50**, a second wall portion **85b** surrounding the left side of the terminal holding portion **50**, a third wall portion **85c** surrounding the front side of the terminal

holding portion **50**, and a fourth wall portion **85d** surrounding the rear side of the terminal holding portion **50** (see FIGS. 4 and 5).

Each of the first wall portion **85a** to the fourth wall portion **85d** is formed in a flat plate shape and arranged vertically, for example.

As shown in FIG. 4, the plate surfaces (wall surfaces) of the first wall portion **85a** and the second wall portion **85b** face in the left-right direction. The plate surfaces (wall surfaces) of the third wall portion **85c** and the fourth wall portion **85d** face in the front-rear direction.

As shown in FIG. 6, in the flange portion **86**, the left-right dimension of the portion jutting out rightward is larger than the left-right dimension of the portion jutting out leftward.

More specifically, in the flange portion **86**, the left-right dimension of the portion jutting out rightward is larger than the left-right dimension of the base portion **12** of the first core member **11a**, and the left-right dimension of the portion jutting out leftward is set to be substantially equal to or slightly larger than the left-right dimension of the base portion **12** of the first core member **11a**.

As described above, the cover member **80** opens downward, for example. The cover member **80** is externally fitted to the bobbin portion **30** by putting the cover member **80** over the bobbin portion **30** from above and pushing the cover member **80** downward against the main body member **20**. Therefore, in the case of this embodiment, the direction in which the cover member **80** is externally fitted to the bobbin portion **30** (which may be hereinafter simply referred to as an externally-fitting direction) is the up-down direction.

In addition, the through openings **88a** and **88b** of the cover member **80** and the through hole **36** of the bobbin portion **30** are arranged coaxially with each other.

As shown in FIGS. 4 and 5, it is preferable that the inner surface of the first wall portion **82a** is arranged to face the right side surface of the first collar portion **41** in parallel. It is preferable that the inner surface of the second wall portion **82b** is arranged to face the left side surface of the second collar portion **42** in parallel. It is preferable that the inner surface of the third wall portion **82c** is arranged to face the front end surface of the first collar portion **41** and the front surface of the second collar portion **42** in parallel. It is preferable that the inner surface of the fourth wall portion **82d** is arranged to face the rear end surface of the first collar portion **41** and the rear surface of the second collar portion **42** in parallel.

As shown in FIG. 6, the inner surface (lower surface) of the top surface portion **81** and each of the upper end surface of the first collar portion **41** and the upper end surface of the second collar portion **42** are close to and face each other, for example. The inner surface of the top surface portion **81** and each of the upper end surface of the first collar portion **41** and the upper end surface of the second collar portion **42** may also be in surface contact with each other.

As shown in FIGS. 4 and 6, it is preferable that the inner surface of the first wall portion **85a** is arranged to face the right side surface of the first terminal holding portion **52** in parallel. It is preferable that the inner surface of the second wall portion **85b** is arranged to face the left side surface of the second terminal holding portion **55** in parallel. It is preferable that the inner surface of the third wall portion **85c** is arranged to face each of the front surface of the first terminal holding portion **52** and the front surface of the second terminal holding portion **55** in parallel. It is preferable that the inner surface of the fourth wall portion **85d** is arranged to face each of the rear surface of the first terminal

11

holding portion 52 and the rear surface of the second terminal holding portion 55 in parallel.

As shown in FIG. 6, it is preferable that the lower surface of the portion of the flange portion 86 of the cover member 80 jutting out rightward from the first wall portion 82a is in surface contact with the upper surface of the first terminal holding portion 52, for example. It is preferable that the lower surface of the portion of the flange portion 86 jutting out leftward from the second wall portion 82b is in surface contact with the upper surface of the second terminal holding portion 55, for example.

The core portion 15 of the first core member 11a is inserted into the through hole 36 of the bobbin portion 30 via the through opening 88a of the first wall portion 82a (the right side of the cover member 80) (see FIG. 1). Similarly, the core portion 15 of the second core member 11b is inserted into the through hole 36 of the bobbin portion 30 via the through opening 88b of the second wall portion 82b (the left side of the cover member 80).

The end surface of the core portion 15 of the first core member 11a and the end surface of the core portion 15 of the second core member 11b abut against each other or are close to each other inside the through hole 36. That is, the end surface of the core portion 15 of the first core member 11a and the end surface of the core portion 15 of the second core member 11b may be in surface contact with each other, or may be close to and face each other.

A closed magnetic circuit is formed by the first core member 11a and the second core member 11b.

As shown in FIG. 4, since the coil 70 is wound around the bobbin portion 30 and the core portion 15 is inserted through the bobbin portion 30, the coil 70 is wound around the magnetic core 10.

As shown in FIG. 4, the front and rear outer leg portions 13 of the first core member 11a are arranged outside the side peripheral wall portion 82, and are provided along the outer surfaces of the third wall portion 82c and the fourth wall portion 82d, respectively. The base portion 12 of the first core member 11a is arranged outside the side peripheral wall portion 82, and the inner side surface 12c of the base portion 12 is arranged to face the outer surface of the first wall portion 82a.

Similarly, the front and rear outer leg portions 13 of the second core member 11b are arranged outside the side peripheral wall portion 82, and are provided along the outer surfaces of the third wall portion 82c and the fourth wall portion 82d, respectively. The base portion 12 of the second core member 11b is arranged outside the side peripheral wall portion 82, and the inner side surface 12c of the base portion 12 is arranged to face or be in surface contact with the outer surface of the second wall portion 82b.

More specifically, as shown in FIG. 4, a gap is formed between the inner side surface 12c of the base portion 12 of the first core member 11a and the outer surface of the first wall portion 82a. On the other hand, a gap may or may not be formed between the inner side surface 12c of the base portion 12 of the second core member 11b and the outer surface of the second wall portion 82b.

The end surface of the front-side outer leg portion 13 of the first core member 11a and the end surface of the front-side outer leg portion 13 of the second core member 11b abut against each other or are close to each other. That is, the end surface of the front-side outer leg portion 13 of the first core member 11a and the end surface of the front-side outer leg portion 13 of the second core member 11b may be in surface contact with each other, or may be close to and face each other. Similarly, the end surface of the

12

rear-side outer leg portion 13 of the first core member 11a and the end surface of the rear-side outer leg portion 13 of the second core member 11b abut against each other or are close to each other.

The base portions 12 and the outer leg portions 13 of the first core member 11a and the second core member 11b are arranged above the flange portion 86 and are arranged along the upper surface 86a of the flange portion 86 (see FIGS. 3 and 6).

The lower surfaces of the core portions 15 are arranged along the inner peripheral bottom surface of the through hole 36.

As shown in FIG. 3, the lower surfaces of the first core member 11a and the second core member 11b are arranged on the same plane. The lower surfaces of the first core member 11a and the second core member 11b are arranged along the upper surface 86a of the flange portion 86. The lower surface of each of the first core member 11a and the second core member 11b and the upper surface 86a of the flange portion 86 may be in surface contact with each other, or may be close to and face each other.

As shown in FIGS. 4 and 6, it is preferable that the outer side surface 12d of the base portion 12 of the first core member 11a is arranged inside or flush with the outer surface of the first wall portion 85a of the second side peripheral wall portion 85. It is preferable that the outer side surface 12d of the base portion 12 of the second core member 11b is arranged inside or flush with the outer surface of the second wall portion 85b of the second side peripheral wall portion 85. It is preferable that each of the outer side surface of the front-side outer leg portion 13 of the first core member 11a and the outer side surface of the front-side outer leg portion 13 of the second core member 11b is arranged inside or flush with the outer surface of the third wall portion 85c of the second side peripheral wall portion 85. It is preferable that each of the outer side surface of the rear-side outer leg portion 13 of the first core member 11a and the outer side surface of the rear-side outer leg portion 13 of the second core member 11b is arranged inside or flush with the outer surface of the fourth wall portion 85d of the second side peripheral wall portion 85.

Thus, in the case of this embodiment, the magnetic core 10 is inserted into the bobbin portion 30 via the cover member 80. Therefore, by maintaining the bobbin portion 30 and the cover member 80 in a good positional relationship, the magnetic core 10 and the coil 70 are also maintained in a good positional relationship, so that more stable characteristics of the coil component 100 can be realized.

In the case of this embodiment, the coil component 100 includes a first fixing tape 90 (see FIGS. 4 and 6) wound around the magnetic core 10. The first fixing tape 90 well maintains the state in which the core portion 15 of each of the first core member 11a and the second core member 11b is inserted in the through hole 36 of the bobbin portion 30.

More specifically, as shown in FIG. 4, the first fixing tape 90 is wound along the outer side surface 12d of the base portion 12 of the second core member 11b, the outer surface of the front-side outer leg portion 13 of the second core member 11b, the outer surface of the front-side outer leg portion 13 of the first core member 11a, the outer side surface 12d of the base portion 12 of the first core member 11a, the outer surface of the rear-side outer leg portion 13 of the first core member 11a, the outer surface of the rear-side outer leg portion 13 of the second core member 11b, and again the outer side surface 12d of the base portion 12 of the second core member 11b, for example.

In the case of this embodiment, the first fixing tape 90 is formed in a band-shape that is long in one direction. The first fixing tape 90 may be a self-adhesive tape on which a self-adhesive layer is formed in advance, or may be a band-shaped member adhered with an adhesive when the coil component 100 is assembled, for example.

Further, in the case of this embodiment, the coil component 100 includes a second fixing tape 95 (see FIGS. 4 and 6) wound around the magnetic core 10 and the cover member 80. The magnetic core 10 is well fixed to each of the bobbin portion 30 and the cover member 80 by the second fixing tape 95.

More specifically, as shown in FIGS. 4 and 6, the second fixing tape 95 is wound along the entire periphery of the outer surface of the first fixing tape 90, and the outer surface of the first wall portion 85a of the second side peripheral wall portion 85, the outer surface of the second wall portion 85b of the second side peripheral wall portion 85, the outer surface of the third wall portion 85c of the second side peripheral wall portion 85, and the outer surface of the fourth wall portion 85d of the second side peripheral wall portion 85, for example.

In the case of this embodiment, the second fixing tape 95 is formed in a band-shape that is long in one direction. For example, the second fixing tape 95 may be a self-adhesive tape on which a self-adhesive layer is formed in advance, or may be a band-shaped member adhered with an adhesive when the coil component 100 is assembled. As shown in FIG. 6, an upper portion of the second fixing tape 95 is wound around the first fixing tape 90.

The up-down dimension of the first fixing tape 90 is set to be substantially equal to the up-down dimension of the magnetic core 10, for example. The up-down dimension of the second fixing tape 95 is larger than the up-down dimension of the magnetic core 10 and smaller than the up-down dimension of the cover member 80, for example.

As shown in FIGS. 4 and 5, it is preferable that each external terminal 65 protrudes outside the outline of the coil component 100 excluding the external terminals 65 in plan view. Further, it is more preferable that the lengths by which the external terminals 65 of the first terminal portion 61 to the third terminal portion 63 protrude from the outline (dimensions W1, W2, W3, and W4 shown in FIG. 4) are substantially equal to each other, and the lengths by which the external terminals 65 of the fourth terminal portion 64 protrude from the outline (dimensions W5 and W6 shown in FIG. 4) are substantially equal to each other.

In the case of this embodiment, since at least one of the cover member 80 and the bobbin portion 30 elastically biases the other in the first direction, which is the extending direction of the tip portion of each external terminal 65, as described above, the relative displacement of the cover member 80 with respect to the bobbin portion 30 in the first direction is restricted. Therefore, it is possible to easily realize and maintain the state in which the external terminals 65 substantially equally protrude outside the outline.

Moreover, it is not necessary to consider the relative displacement of the cover member 80 with respect to the bobbin portion 30 in the first direction (left-right direction) when setting the left-right dimension of each external terminal 65, and it is possible to set the entire outer dimension of the coil component 100 including the external terminals 65 to be smaller.

In the case of this embodiment, as an example, each of the dimensions W1 to W4 is a length dimension from the right side surface of the second fixing tape 95 to the end surface of each external terminal 65 of the first terminal portion 61

to the third terminal portion 63 in the first direction, and each of the dimensions W4 and W5 is a length dimension from the left side surface of the second fixing tape 95 to the end surface of each external terminal 65 of the fourth terminal portion 64 in the first direction.

Each of the first core member 11a and the second core member 11b is integrally formed of a magnetic material in its entirety.

The main body member 20 (the bobbin portion 30 and the terminal holding portion 50) is integrally formed of an insulating material such as resin in its entirety, for example.

The cover member 80 is integrally formed of an insulating material such as resin in its entirety, for example.

As shown in FIG. 3, the bobbin portion 30 includes a first side surface 45 arranged along the first wall portion 82a and a second side surface 48 arranged along the second wall portion 82b, for example.

In addition, at least one of the first wall portion 82a and the first side surface 45 elastically biases the other in the first direction. Further, the second side surface 48 and the second wall portion 82b are formed flat and are in surface contact with each other.

In this manner, when the cover member 80 is externally fitted to the bobbin portion 30, by arranging the second side surface 48 and the second wall portion 82b to be in surface contact with each other, it is possible to easily position the cover member 80 with respect to the bobbin portion 30 without using a dedicated jig. Moreover, since the state in which the second side surface 48 and the second wall portion 82b are in surface contact with each other is maintained well, it is possible to restrict the relative displacement of the cover member 80 with respect to the bobbin portion 30 around each of the Z axis and the Y axis. Therefore, it is possible to more easily realize and maintain the state in which the above-mentioned dimensions W1 to W4 are equal to each other and the above-mentioned dimensions W5 and W6 are equal to each other.

Moreover, when setting the length dimension of each external terminal 65 in the first direction, by considering the length dimension from the second side surface 48 to the end surface of each external terminal 65 of the first terminal portion 61 to the third terminal portion 63 in the first direction and the length dimension from the second side surface 48 to the end surface of each external terminal 65 of the fourth terminal portion 64 in the first direction, the above-described arrangement can be easily realized. Therefore, it is possible to set the entire outer dimension of the coil component 100 including the external terminals 65 to be further smaller.

As shown in FIG. 3, in the case of this embodiment, the first side surface 45 is formed by the right side surface of the first collar portion 41. The second side surface 48 is formed by the left side surface of the second collar portion 42, for example.

Therefore, the first side surface 45 (a reference surface 49, which will be described later) is orthogonal to the first direction (in the case of this embodiment, the left-right direction). Also, the second side surface 48 is orthogonal to the first direction (in the case of this embodiment, the left-right direction). The first side surface 45 is arranged to face rightward, and the second side surface 48 is arranged to face leftward.

As shown in FIGS. 3 and 8, at least one of the cover member 80 and the bobbin portion 30 has a spring piece 83 that elastically biases the other, for example. In the case of this embodiment, the cover member 80 has the spring piece

83, and the cover member 80 elastically biases the bobbin portion 30 by means of the spring piece 83, as an example.

The spring piece 83 can elastically deform toward one side in the first direction. When the cover member 80 is being externally fitted to the bobbin portion 30, by pushing the cover member 80 downward against the bobbin portion 30, the cover member 80 is pressed by the bobbin portion 30, so that the spring piece 83 elastically deforms toward one side in the first direction and the spring piece 83 elastically biases the bobbin portion 30 toward the other side in the first direction (which may be hereinafter simply referred to as a biasing direction).

Thus, since the bobbin portion 30 is elastically biased by the spring piece 83 which can elastically deform by a sufficient amount of displacement, even if there is a manufacturing variation in the dimension of either one or both of the bobbin portion 30 and the cover member 80 in the first direction, the spring piece 83 elastically deforms in conformity with the manufacturing variation, so that the manufacturing variation can be better absorbed. Therefore, the cover member 80 can suitably bias the bobbin portion 30 regardless of the manufacturing variation.

In the case of this embodiment, as an example, a portion of the first wall portion 82a of the cover member 80 forms the spring piece 83, and the cover member 80 (the first wall portion 82a) elastically biases the bobbin portion 30 (the first side surface 45) by means of the spring piece 83. Further, as shown in FIG. 6, the first side surface 45 is arranged on the left side of the spring piece 83. Therefore, the biasing direction of the spring piece 83 is the leftward direction, which coincides with the direction in which the second side surface 48 faces. Thus, the second side surface 48 is biased leftward (toward the second wall portion 82b) by the spring piece 83 and is in good surface contact with the inner surface of the second wall portion 82b.

As shown in FIGS. 6 and 8, in the case of this embodiment, the spring piece 83 has a cantilever structure, as an example. More specifically, one end of the spring piece 83 is supported while the other end is not supported.

This makes it possible to realize a structure in which the spring piece 83 can elastically deform by a more and sufficient amount of displacement. Therefore, the cover member 80 can be smoothly externally fitted to the bobbin portion 30, and the cover member 80 can elastically bias the bobbin portion 30 well.

Note that the spring piece 83 is not limited to the cantilever structure, and may have a double-support structure in which one and the other ends of the spring piece 83 are both supported.

The spring piece 83 has a cantilever structure in which one end portion of the spring piece 83 in the direction in which the cover member 80 is externally fitted to the bobbin portion 30 is supported.

In this manner, for example, if the first side surface 45 has irregularities formed along the externally-fitting direction, the spring piece 83 can elastically deform in the first direction to conform to the irregularities when the cover member 80 is externally fitted to the bobbin portion 30. Therefore, the contact of the spring piece 83 with the bobbin portion 30 can be suppressed.

As shown in FIG. 8, the spring piece 83 is formed to extend downward from the upper edge of the through opening 88a formed in the first wall portion 82a. That is, the upper end portion (a base end portion 83a, which will be described later) of the spring piece 83 is supported by the first wall portion 82a. More specifically, the upper end portion of the spring piece 83 is a fixed end, and the lower

end portion (a tip portion 83c, which will be described later) of the spring piece 83 is a free end.

Note that, for example, the spring piece 83 may also be formed to extend upward from the lower edge of the through opening 88a formed in the first wall portion 82a. That is, the upper end portion (the base end portion 83a, which will be described later) of the spring piece 83 may be a free end, and the lower end portion (the tip portion 83c, which will be described later) of the spring piece 83 may be a fixed end.

Note that the extending direction of the spring piece 83 is not limited to the externally-fitting direction, and may be the second direction, for example.

In addition, in the case of this embodiment, at least one part of the spring pieces 83 may be arranged along the first side surface 45. Thus, for example, the spring piece 83 may be formed by a portion of the top surface portion 81 and a portion of the first wall portion 82a.

As shown in FIGS. 1, 2, and 8, the spring piece 83 is formed at each of the front and rear portions of the first wall portion 82a such that the through hole 36 of the bobbin portion 30 is interposed therebetween in the front-rear direction, for example. In other words, the through hole 36 is arranged between the front-side spring piece 83 and the rear-side spring piece 83. Thus, the two spring pieces 83 are formed to be arranged side by side in the front-rear direction, that is, in a direction orthogonal to the first direction, and it is thus possible to realize a structure in which the spring pieces 83 better elastically biases the first side surface 45 in the first direction.

The spring pieces 83 extend in parallel to each other, for example.

Each spring piece 83 is a leaf spring formed in a substantially flat plate shape, for example.

The shape of each spring piece 83 as viewed in the first direction (left-right direction) is a substantially rectangular shape that is long in the up-down direction, for example. The thickness dimension of the spring piece 83 is substantially constant at any position in the up-down direction and is set to be equal to the thickness dimension of the first wall portion 82a.

As shown in FIG. 6, the spring piece 83 bends convexly toward one side (rightward) in the first direction and also bends convexly toward the other side (leftward) in the first direction.

More specifically, each spring piece 83 includes a base end portion 83a connected to the first wall portion 82a, a bending portion 83b connected to the base end portion 83a, and a tip portion 83c connected to the bending portion 83b, for example.

The base end portion 83a extends downward from the upper edge of the through opening 88a, and the bending portion 83b bends such that the amount of leftward displacement increases downward from the lower edge of the base end portion 83a. The tip portion 83c extends downward from the lower edge of the bending portion 83b.

Further specifically, the boundary between the outer surface of the base end portion 83a and the outer surface of the bending portion 83b protrudes outside the outer surface of the first wall portion 82a, for example. In addition, it is preferable that the boundary between the inner surface 831b of the bending portion 83b and the inner surface 831c of the tip portion 83c protrudes inside the inner surface of the first wall portion 82a or is located on the same plane as the inner surface of the first wall portion 82a, for example.

In the case of this embodiment, as described above, a gap is formed between the inner side surface 12c of the base portion 12 of the first core member 11a and the outer surface

of the first wall portion **82a** (see FIG. 4). This prevents the spring piece **83** and the base portion **12** from making contact with each other even though the spring piece **83** partially protrudes outside (to the right side of) the outer surface of the first wall portion **82a**.

Each spring piece **83** is formed integrally with the cover member **80**, for example. Therefore, the spring piece **83** is formed of the same type of resin material as the resin material forming the cover member **80**.

However, the spring piece **83** may be incorporated into the cover member **80** by insert molding, for example. In this case, the spring piece **83** is formed of metal. The spring piece **83** may also be formed separately from the cover member **80**, for example, fixed to the cover member **80** with an adhesive or the like. In this case, the spring piece **83** may be formed of the same type of resin material as the resin material forming the cover member **80**, or may be formed of another material such as metal.

Further, in the case of this embodiment, in the coil component **100**, one of the cover member **80** and the bobbin portion **30** (in the case of this embodiment, the cover member **80** as an example) has the spring piece **83**, and the other of the cover member **80** and the bobbin portion **30** (in the case of this embodiment, the bobbin portion **30** as an example) has a bulging portion **46** bulging toward the spring piece **83**.

In this manner, it is possible to better ensure that the spring piece **83** contacts the bobbin portion **30** (the bulging portion **46**) when the cover member **80** is externally fitted to the bobbin portion **30**. Therefore, it is possible to better ensure that the relative displacement of the bobbin portion **30** with respect to the cover member **80** in the first direction is restricted.

More specifically, the bulging portion **46** bulges in a direction opposite to the biasing direction of the spring piece **83** (the other side in the first direction), that is, toward the one side in the first direction, for example. The spring piece **83** is elastically deformed toward the one side in the first direction by being pressed toward the one side by the bulging portion **46**.

More specifically, in the case of this embodiment, the bulging portion **46** is formed on the first side surface **45** of the bobbin portion **30**, as an example. The spring piece **83** is arranged on the right side of the first side surface **45**. Therefore, the direction in which the bulging portion **46** bulges is the rightward direction, which coincides with the direction in which the inner surface of the second wall portion **82b** faces. Thus, the second side surface **48** is further biased leftward (toward the second wall portion **82b**) by the bulging portion **46** and is in good surface contact with the inner surface of the second wall portion **82b**.

The bulging portion **46** is formed on the first side surface **45** at a position corresponding to each of the pair of spring pieces **83**. Therefore, the bulging portion **46** is formed at each of front and rear portions of the first side surface **45** such that the through hole **36** is interposed therebetween in the front-rear direction, as an example. In other words, the through hole **36** is arranged between the front-side bulging portion **46** and the rear-side bulging portion **46**.

It is preferable that, in at least a portion of the bulging portion **46**, the amount by which the bulging portion **46** bulges toward the other of the cover member **80** and the bobbin portion **30** increases in the direction in which the cover member **80** is externally fitted to the bobbin portion **30**, for example.

As shown in FIG. 6, in the case of this embodiment, the amount by which the bulging portion **46** bulges toward the cover member **80** increases downward, as an example.

In this manner, the biasing force of the spring piece **83** on the bobbin portion **30** increases downward, so that it is possible to realize a structure in which the spring piece **83** well elastically biases the bobbin portion **30** when the cover member **80** is externally fitted to the bobbin portion **30**.

Moreover, as described above, in the case of this embodiment, the spring piece **83** has a cantilever structure in which the upper end portion (the base end portion **83a**) of the spring piece **83** in the direction in which the cover member **80** is externally fitted to the bobbin portion **30** is supported. Thus, when the cover member **80** is externally fitted to the bobbin portion **30**, the spring piece **83** can well elastically deform along the shape of the bulging portion **46**, of which the amount of bulge toward the cover member **80** increases in the externally-fitting direction (downward).

As shown in FIG. 6, each bulging portion **46** includes a tapered portion **46a** in which the amount of bulge increases downward in a tapered manner and a flat portion **46b** formed flat and arranged vertically.

Each of the tapered portion **46a** and the flat portion **46b** is arranged to face the inner surface of the first wall portion **82a**.

The flat portion **46b** is orthogonal to the first direction (in the case of this embodiment, the left-right direction), for example.

The upper edge of each tapered portion **46a** is connected to the lower edge of a guiding portion **47**, which will be described later, and the lower edge of each tapered portion **46a** is connected to the upper edge of the corresponding flat portion **46b**. The lower edge of each flat portion **46b** is connected to the upper surface of the first terminal holding portion **52**.

Further, on the first side surface **45**, a pair of front and rear guiding portions **47** (see FIG. 9A) in which the amount of bulge decreases upward in a tapered manner is formed above the respective bulging portions **46**. The front-side guiding portion **47** is formed continuously with the tapered portion **46a** of the front-side bulging portion **46**, and the rear-side guiding portion **47** is formed continuously with the tapered portion **46a** of the rear-side bulging portion **46**. Each guiding portion **47** is formed from the upper end of the first side surface **45** to the upper edge of the tapered portion **46a**, for example.

As shown in FIGS. 3, 6 and 9B, the bulging portion **46** (the tapered portion **46a** and the flat portion **46b**) protrudes rightward (toward the first wall portion **82a**) beyond the portion of the first side surface **45** other than the bulging portion **46** and the guiding portion **47** (hereinafter, a reference surface **49**). More specifically, the outer side surface of the bulging portion **46** is arranged on the left side of the right side surface of the first terminal holding portion **52**.

The guiding portion **47** is arranged on the left side of the reference surface **49**.

The inclination angle of the guiding portion **47** with respect to the reference surface **49** and the inclination angle of the tapered portion **46a** with respect to the reference surface **49** are set to be equal to each other, and the inclined surface of the guiding portion **47** and the inclined surface of the tapered portion **46a** are arranged on the extension of each other. Therefore, the inclined surface of the guiding portion **47** and the inclined surface of the tapered portion **46a** are arranged flush with each other (see FIGS. 6 and 9B).

Each of the guiding portion **47** and the tapered portion **46a** is formed to extend in the up-down direction. The front-rear

dimension of the guiding portion 47 and the front-rear dimension of the tapered portion 46a are set to be equal to each other. Therefore, the combined portion of the guiding portion 47 and the tapered portion 46a has a straight line-shape extending in the up-down direction in side view, for example.

In addition, a notch-shaped portion 45a that opens upward and in the left-right direction is formed at a portion of the upper end surface of the first collar portion 41 interposed between the front-side guiding portion 47 and the rear-side guiding portion 47 (see FIGS. 9A and 9C).

When the cover member 80 is externally fitted to the bobbin portion 30, the pair of spring pieces 83 is guided along the corresponding guiding portions 47 toward the bulging portions 46.

Here, as shown in FIG. 6, in the case of this embodiment, it is preferable that the tip portion 83c of the spring piece 83 has a contact portion 84 that contacts the other of the cover member 80 and the bobbin portion 30 (in the case of this embodiment, the bobbin portion 30 as an example) and biases the other (the bobbin portion 30), and a portion of the spring piece 83 closer to the base end than the contact portion 84 is separated from the other (the bobbin portion 30).

This can reduce the area of the contact portion 84 (the spring piece 83) in contact with the bobbin portion 30. Therefore, the spring piece 83 can be positioned appropriately (at an intended position) with respect to the bobbin portion 30 regardless of the size or the inclination angle of the portion of the bobbin portion 30 in contact with the contact portion 84.

The contact portion 84 may be in line contact, point contact, or surface contact with the other (the bobbin portion 30), for example. When the contact portion 84 is in surface contact with the bobbin portion 30, it is preferable that the height dimension (up-down dimension) of the contact portion 84 is smaller than its width dimension (front-rear dimension). When the height dimension of the contact portion 84 becomes further smaller than its width dimension, it becomes line contact. That is, that the contact portion 84 is in line contact with the bobbin portion 30 means that the height dimension of the contact portion 84 is significantly smaller than its width dimension.

Among these, in this embodiment, it is more preferable that the contact portion 84 is in line contact or point contact with the other (the bobbin portion 30), and a portion of the tip portion 83c of the spring piece 83 closer to the tip end than the contact portion 84 is separated from the other (the bobbin portion 30).

This can further reduce the area of the contact portion 84 (the spring piece 83) in contact with the bobbin portion 30. Therefore, the spring piece 83 can be positioned appropriately (at an intended position) with respect to the bobbin portion 30 regardless of the size or the inclination angle of the portion of the bobbin portion 30 in contact with the contact portion 84.

In the case of this embodiment, as shown in FIG. 6, the boundary between the inner surface 831b of the bending portion 83b and the inner surface 831c of the tip portion 83c is the contact portion 84 against the bobbin portion 30. The contact portion 84 is in line contact with the flat portion 46b of the bulging portion 46 along the front-rear direction, for example.

More specifically, the bending portion 83b is inclined rightward with respect to the flat portion 46b in the upward direction, for example. The tip portion 83c is inclined rightward with respect to the flat portion 46b in the down-

ward direction, for example. Further specifically, the bending portion 83b is gradually separated away from the flat portion 46b in the upward direction with respect to the contact portion 84, and the tip portion 83c is gradually separated away from the flat portion 46b in the downward direction with respect to the contact portion 84.

Thus, since the coil component 100 has a structure in which the spring piece 83 is in line contact with the flat portion 46b orthogonal to the first direction, the cover member 80 can well bias the bobbin portion 30 toward the other side (left side) in the first direction.

FIG. 7 illustrates a state before the cover member 80 is externally fitted to the bobbin portion 30, that is, a state in which no external force is acting on the spring piece 83. In FIG. 7, the flat portion 46b of the bulging portion 46 is indicated by a long dashed double-short dashed line for convenience.

As shown in FIG. 7, before the cover member 80 is externally fitted to the bobbin portion 30, the outer and inner surfaces of the base end portion 83a are orthogonal to the first direction (left-right direction). The outer surface of the base end portion 83a is arranged flush with the outer surface of the portion of the first wall portion 82a other than the spring piece 83 (hereinafter, a main portion 821a), for example, and the inner surface of the base end portion 83a is arranged flush with the inner surface of the main portion 821a, for example.

Similarly, before the cover member 80 is externally fitted to the bobbin portion 30, the outer surface and the inner surface 831c of the tip portion 83c are orthogonal to the first direction (left-right direction). The outer surface of the tip portion 83c is arranged inside the outer surface of the main portion 821a, and the inner surface 831c of the tip portion 83c is arranged inside the inner surface of the main portion 821a.

Further, before the cover member 80 is externally fitted to the bobbin portion 30, the outer surface of the bending portion 83b is arranged inside the outer surface of the main portion 821a, and the inner surface 831b of the bending portion 83b is arranged inside the inner surface of the main portion 821a, for example.

Therefore, before the cover member 80 is inserted into the bobbin portion 30, a portion of the spring piece 83 (for example, the bending portion 83b and the tip portion 83c) bends in the biasing direction, that is, toward the other side in the first direction beyond the main portion 821a. More specifically, as shown in FIG. 7, a portion of the spring piece 83 (the inner surface 831b of the bending portion 83b and the inner surface 831c of the tip portion 83c) is located beyond the flat portion 46b in the biasing direction (leftward direction).

In this manner, even if there is a manufacturing variation in the dimension of the bobbin portion 30 in the first direction, the spring piece 83 stably contacts the flat portion 46b, so that the cover member 80 can well elastically biases the first side surface 45 (the bobbin portion 30).

In the case of this embodiment, when the cover member 80 is externally fitted to the bobbin portion 30, the spring piece 83 is pressed rightward by the bulging portion 46 and swings (elastically deforms) rightward, that is, in the direction opposite to the biasing direction with respect to a fulcrum at the boundary between the base end portion 83a and the first wall portion 82a.

Further, as shown in FIGS. 1 and 8, in the case of this embodiment, at least one of the third wall portion 82c and the fourth wall portion 82d is fitted to the bobbin portion 30 in a fitting structure.

In this manner, the relative displacement of the cover member **80** with respect to the bobbin portion **30** is restricted in the direction parallel to the mounting surface and orthogonal to the first direction, namely the second direction. More specifically, for example, it is possible to position the main body member **20** including the bobbin portion **30** at a desired position in the front-rear direction in the internal space of the cover member **80**. Therefore, in the case of this embodiment, for example, it is possible to arrange the main body member **20** at the center in the front-rear direction and to well maintain this positional relationship.

Moreover, since the cover member **80** is fitted to the bobbin portion **30**, it is possible to inhibit the bobbin portion **30** from falling out of the cover member **80** in the up-down direction.

In the case of this embodiment, both of the third wall portion **82c** and the fourth wall portion **82d** are fitted to the bobbin portion **30** in a fitting structure.

More specifically, as shown in FIGS. 2, 4, etc., the first terminal holding portion **52** has a first projecting portion **53a** protruding from the front surface of the first terminal holding portion **52** toward one side (front side) in the second direction, and a first projecting portion **53b** protruding from the rear surface of the first terminal holding portion **52** toward the other side (rear side) in the second direction. Similarly, the second terminal holding portion **55** has a second projecting portion **56a** protruding from the front surface of the second terminal holding portion **55** toward one side (front side) in the second direction, and a second projecting portion **56b** protruding from the rear surface of the second terminal holding portion **55** toward the other side (rear side) in the second direction.

Further, as shown in FIG. 2, for example, first slit portions **89a** are formed at respective portions of the third wall portion **85c** of the second side peripheral wall portion **85** corresponding to the first projecting portion **53a** and the second projecting portion **56a**. Each first slit portion **89a** is formed to penetrate the third wall portion **85c** in the second direction (front-rear direction), for example. However, instead of the first slit portion **89a**, a first concave portion (not shown in the drawings) recessed frontward from the inner surface of the third wall portion **85c** may be formed. Each first slit portion **89a** extends in a substantially straight line in the left-right direction, for example.

Similarly, as shown in FIG. 2, for example, second slit portions **89b** are formed at respective portions of the fourth wall portion **85d** of the second side peripheral wall portion **85** corresponding to the first projecting portion **53b** and the second projecting portion **56b**. Each second slit portion **89b** is formed to penetrate the fourth wall portion **85d** in the second direction (front-rear direction), for example. However, instead of the second slit portion **89b**, a second concave portion (not shown in the drawings) recessed rearward from the inner surface of the fourth wall portion **85d** may be formed. Each second slit portion **89b** extends in a substantially straight line in the left-right direction, for example.

Each of the first projecting portion **53a** and the second projecting portion **56a** is fitted to the corresponding first slit portion **89a**. Similarly, each of the first projecting portion **53b** and the second projecting portion **56b** is fitted to the corresponding second slit portion **89b**.

Thus, since both of the third wall portion **82c** and the fourth wall portion **82d** are fitted to the bobbin portion **30** in a fitting structure, it is possible to restrict the relative

displacement of the cover member **80** with respect to the bobbin portion **30** around each of the X axis and the Y axis. In this manner, it is possible to better maintain the state in which the cover member **80** is externally fitted to the bobbin portion **30**.

In the case of this embodiment, the length by which the first projecting portion **53a** protrudes and the length by which the first projecting portion **53b** protrudes are set to be equal to each other. Similarly, the length by which the second projecting portion **56a** protrudes and the length by which the second projecting portion **56b** protrudes are set to be equal to each other. In addition, the length by which the first projecting portions **53a** and **53b** protrude and the length by which the second projecting portions **56a** and **56b** protrude are set to be equal to each other.

Each of the first projecting portion **53a** and the second projecting portion **56a** and each first slit portion **89a** may be further fixed to each other with an adhesive or the like, which is not shown in the drawings. Similarly, each of the first projecting portion **53b** and the second projecting portion **56b** and each second slit portion **89b** may be further fixed to each other with an adhesive or the like, which is not shown in the drawings.

The coil component **100** according to this embodiment is constituted as described above. This coil component **100** can be used as a high withstand voltage pulse transformer, as an example. However, the use of the coil component **100** is not limited to this example.

The coil component **100** can be assembled as follows, for example.

First, each winding wire **71** of the coil **70** (the first coil and the second coil) is wound around the tubular portion **31** of the bobbin portion **30**. Each end portion of each winding wire **71** is entwined around the entwining terminal **66** of the corresponding terminal portion **60** and is fixed by welding or soldering.

Next, the cover member **80** is put over the bobbin portion **30** from above. At this time, for example, the tip portion **83c** of the spring piece **83** is first arranged along the corresponding guiding portion **47** of the first side surface **45**, and the inner surface of the second wall portion **82b** is arranged in surface contact with the second side surface **48**. Then, the cover member **80** is pushed downward against the main body member **20** until each of the first projecting portion **53a** and the second projecting portion **56a** is fitted to the corresponding first slit portion **89a** and each of the first projecting portion **53b** and the second projecting portion **56b** is fitted to the corresponding second slit portion **89b**. At this time, the boundary between the bending portion **83b** and the tip portion **83c** of the spring piece **83** slides downward along the inclined surface of the guiding portion **47** and the inclined surface of the tapered portion **46a** to reach the flat portion **46b**. In this manner, the cover member **80** is externally fitted to the bobbin portion **30**.

Next, the core portion **15** of the first core member **11a** is inserted into the through hole **36** from the through opening **88a**, while the core portion **15** of the second core member **11b** is inserted into the through hole **36** from the through opening **88b**.

Next, the first fixing tape **90** is wound around the magnetic core **10** at least once. In this manner, the magnetic core **10** can be fixed to the cover member **80** and the bobbin portion **30**. Further, the second fixing tape **95** is wound around each of the first fixing tape **90** and the second side peripheral wall portion **85** of the cover member **80** at least

once (see FIGS. 4 and 6). In this manner, the magnetic core 10 can be more securely fixed to the cover member 80 and the main body member 20.

The coil component 100 is thus obtained.

Although the embodiments have been described above with reference to the drawings, they are merely examples of the present invention, and various arrangements other than the above may be adopted.

For example, although an example in which the cover member 80 elastically biases the bobbin portion 30 has been described above, the present invention is not limited to this example, and the bobbin portion 30 may elastically bias the cover member 80. That is, the bobbin portion 30 may be elastically deformed, and the bobbin portion 30 may elastically bias the cover member 80 by means of its elastic restoring force.

In this case, for example, the bobbin portion 30 may have a spring piece 83 that elastically biases the cover member 80, and the cover member 80 may have a bulging portion 46 bulging toward the spring piece 83.

Further, in the present invention, the cover member 80 may elastically bias the bobbin portion 30 and the bobbin portion 30 may elastically bias the cover member 80. That is, the cover member 80 may be elastically deformed and the cover member 80 may elastically bias the bobbin portion 30 by means of its elastic restoring force, and the bobbin portion 30 may be elastically deformed and the bobbin portion 30 may elastically bias the cover member 80 by means of its elastic restoring force.

In this case, the direction in which the cover member 80 elastically biases the bobbin portion 30 and the direction in which the bobbin portion 30 elastically biases the cover member 80 may be directions that are parallel to the mounting surface and are different from each other (for example, orthogonal to each other). In other words, for example, the cover member 80 may elastically bias the bobbin portion 30 in the first direction, and the bobbin portion 30 may elastically bias the cover member 80 in the second direction. In addition, the cover member 80 may elastically bias the bobbin portion 30 toward the other side in the first direction and the bobbin portion 30 may elastically bias the cover member 80 toward the one side in the first direction, or vice versa.

In addition, although an example in which the cover member 80 elastically biases the bobbin portion 30 toward the other side in the first direction has been described above, the present invention is not limited to this example, and the cover member 80 may elastically bias the bobbin portion 30 toward both of the one side in the first direction and the other side in the first direction.

More specifically, for example, the cover member 80 may have spring pieces 83 that elastically bias the bobbin portion 30 on both of the one side in the first direction (the first wall portion 82a) and the other side in the first direction (the second wall portion 82b). In this case, it is preferable that bulging portions 46 bulging toward the cover member 80 are formed on both of the first side surface 45 and the second side surface 48 of the bobbin portion 30.

Even in this case, the bobbin portion 30 may elastically bias the cover member 80 as described above. That is, the bobbin portion 30 may elastically bias the cover member 80 toward both of the one side in the first direction and the other side in the first direction.

In addition, although an example in which the cover member 80 elastically biases the bobbin portion 30 by means of the spring piece 83 has been described above, the present invention is not limited to this example, and a

tapered portion protruding toward the bobbin portion 30 in a tapered manner may be formed on the inner surface of the cover member 80, and the tapered portion may be elastically pressed against the bobbin portion 30, so that the cover member 80 may elastically bias the bobbin portion 30. In this case, as an example, it is preferable that the amount by which the upper portion of the tapered portion bulges toward the bobbin portion 30 gradually increases toward one side in the externally-fitting direction, and the amount by which the other portion (lower portion) of the tapered portion bulges toward the bobbin portion 30 gradually decreases toward the other side in the externally-fitting direction. In this manner, the cover member 80 can be smoothly externally fitted to the bobbin portion 30, and the tapered portion can well elastically bias the bobbin portion 30.

Even in this case, the bobbin portion 30 may elastically bias the cover member 80 as described above. That is, a tapered portion protruding toward the cover member 80 in a tapered manner may be formed on the outer surface of the bobbin portion 30.

In addition, although an example in which the magnetic core 10 includes two E cores has been described above, the present invention is not limited to this example, and the magnetic core 10 may include an E core and an I core.

Further, the magnetic core 10 may include two T cores, or may include a T core and an I core. In this case, the entire shape of the magnetic core 10 is H-shaped in plan view.

In addition, although an example in which the magnetic core 10 includes the core portion 15 has been described above, the magnetic core 10 may not include the core portion 15. That is, the magnetic core 10 may include two U-shaped core members, or may include a U-shaped core member and an I-shaped core member. In this case, the entire shape of the magnetic core 10 is a rectangular annular shape in plan view.

In addition, although an example in which the magnetic core 10 includes two members (the first core member 11a and the second core member 11b) has been described above, the magnetic core 10 may be one piece in its entirety, or may include three or more members.

This embodiment encompasses the following technical ideas.

- (1) A coil component comprising:
a bobbin portion;
a magnetic core inserted through the bobbin portion;
a coil wound around the bobbin portion; and
a cover member covering the bobbin portion by being externally fitted to the bobbin portion, wherein the cover member and the bobbin portion abut each other, and at least one of the cover member and the bobbin portion elastically biases the other in a first direction parallel to a mounting surface.
- (2) The coil component according to (1), wherein at least one of the cover member and the bobbin portion comprises a spring piece that elastically biases the other.
- (3) The coil component according to (2), wherein the spring piece has a cantilever structure.
- (4) The coil component according to (3), wherein the spring piece has a cantilever structure in which one end portion of the spring piece in a direction in which the cover member is externally fitted to the bobbin portion is supported.
- (5) The coil component according to (3) or (4), wherein a tip portion of the spring piece comprises a contact portion that contacts and biases the other of the cover member and the bobbin portion, and

25

a portion of the spring piece closer to a base end than the contact portion is separated from the other.

(6) The coil component according to (5), wherein the contact portion is in line contact or point contact with the other, and

a portion of the tip portion of the spring piece that is closer to a tip end than the contact portion is separated from the other.

(7) The coil component according to any one of (2) to (6), wherein

one of the cover member and the bobbin portion comprises the spring piece, and

the other of the cover member and the bobbin portion comprises a bulging portion bulging toward the spring piece.

(8) The coil component according to (7), wherein in at least a portion of the bulging portion, an amount by which the bulging portion bulges toward the other of the cover member and the bobbin portion increases in a direction in which the cover member is externally fitted to the bobbin portion.

(9) The coil component according to any one of (1) to (8), wherein

the cover member comprises a side peripheral wall portion including a first wall portion and a second wall portion facing each other,

the bobbin portion comprises a first side surface arranged along the first wall portion,

at least one of the first wall portion and the first side surface elastically biases the other in the first direction, the bobbin portion comprises a second side surface arranged along the second wall portion, and

the second side surface and the second wall portion are formed flat and are in surface contact with each other.

(10) The coil component according to any one of (1) to (9), wherein

the cover member comprises a side peripheral wall portion having a rectangular tubular shape and including a first wall portion, a second wall portion, a third wall portion, and a fourth wall portion, the first wall portion and the second wall portion face each other, and the third wall portion and the fourth wall portion face each other,

a direction in which the first wall portion and the second wall portion face each other is the first direction,

a direction in which the third wall portion and the fourth wall portion face each other is a second direction orthogonal to the first direction, and

at least one of the third wall portion and the fourth wall portion is fitted to the bobbin portion in a fitting structure.

What is claimed is:

1. A coil component comprising:

a bobbin portion;

a magnetic core inserted through the bobbin portion;

a coil wound around the bobbin portion; and

a cover member covering the bobbin portion by being externally fitted to the bobbin portion, wherein

the cover member and the bobbin portion abut each other, and at least one of the cover member and the bobbin portion elastically biases the other of the cover member

and the bobbin portion in a first direction parallel to an axial direction of the coil,

26

at least one of the cover member and the bobbin portion includes a spring piece that elastically biases the other of the cover member and the bobbin portion, the spring piece has a cantilever structure,

5 a tip portion of the spring piece includes a contact portion that contacts and biases the other of the cover member and the bobbin portion, and

a portion of the spring piece closer to a base end than the contact portion is separated from the other of the cover member and the bobbin portion.

2. The coil component according to claim 1, wherein the spring piece has the cantilever structure in which one end portion of the spring piece in a direction in which the cover member is externally fitted to the bobbin portion is supported.

3. The coil component according to claim 1, wherein the contact portion is in line contact or point contact with the other of the cover member and the bobbin portion, and

a portion of the tip portion of the spring piece that is closer to a tip end than the contact portion is separated from the other of the cover member and the bobbin portion.

4. A coil component comprising:

a bobbin portion;

a magnetic core inserted through the bobbin portion;

a coil wound around the bobbin portion; and

a cover member covering the bobbin portion by being externally fitted to the bobbin portion, wherein

the cover member and the bobbin portion abut each other, and at least one of the cover member and the bobbin portion elastically biases the other of the cover member and the bobbin portion in a first direction parallel to an axial direction of the coil,

30 at least one of the cover member and the bobbin portion includes a spring piece that elastically biases the other of the cover member and the bobbin portion, and

the other of the cover member and the bobbin portion includes a bulging portion bulging toward the spring piece.

40 5. The coil component according to claim 4, wherein in at least a portion of the bulging portion, an amount by which the bulging portion bulges toward the other of the cover member and the bobbin portion increases in a direction in which the cover member is externally fitted to the bobbin portion.

6. A coil component comprising:

a bobbin portion;

a magnetic core inserted through the bobbin portion;

a coil wound around the bobbin portion; and

a cover member covering the bobbin portion by being externally fitted to the bobbin portion, wherein

the cover member and the bobbin portion abut each other, and at least one of the cover member and the bobbin portion elastically biases the other of the cover member and the bobbin portion in a first direction parallel to an axial direction of the coil,

55 the cover member includes a side peripheral wall portion including a first wall portion and a second wall portion facing each other,

the bobbin portion includes a first side surface arranged along the first wall portion,

at least one of the first wall portion and the first side surface elastically biases the other in the first direction, the bobbin portion includes a second side surface

arranged along the second wall portion, and

the second side surface and the second wall portion are formed flat and are in surface contact with each other.

7. The coil component according to claim 1, wherein the cover member includes a side peripheral wall portion having a rectangular tubular shape and including a first wall portion, a second wall portion, a third wall portion, and a fourth wall portion, the first wall portion and the second wall portion face each other, and the third wall portion and the fourth wall portion face each other, a direction in which the first wall portion and the second wall portion face each other is the first direction, a direction in which the third wall portion and the fourth wall portion face each other is a second direction orthogonal to the first direction, and at least one of the third wall portion and the fourth wall portion is fitted to the bobbin portion in a fitting structure.
